UNITED STATES PATENT OFFICE.

JOSEPH J. McCANN, OF CINCINNATI, OHIO.

BOILER-COUPING.

1,321,235.

Specification of Letters Patent. Patented Nov. 11, 1919.

Application filed February 1, 1919. Serial No. 274,401.

To all whom it may concern:

Be it known that I, JOSEPH J. McCANN, a citizen of the United States, and a resident of Cincinnati, in the county of Hamilton and State of Ohio, have invented new and useful Improvements in Boiler-Couplings, of which the following is a specification.

My invention is an improvement in boiler couplings, and has for its object to provide a simple and efficient coupling of the character specified.

In the drawings:

Figure 1 is a perspective view of a boiler provided with the improved coupling, a part 15 of the boiler being broken away;

Fig. 2 is an enlarged vertical section of the coupling;

Fig. 3 is a section on the line 3—3 of Fig. 2;

Fig. 4 is a perspective view of the coupling applied to a boiler supplied with overhead pipes;

Fig. 5 is an enlarged section of the top of the coupling, showing a modified arrangement;

Fig. 6 is a section on the line 6—6 of Fig. 5, looking in the direction of the arrows adjacent the line;

Fig. 7 is a section on the line 7—7 of Fig. 4, looking in the direction of the arrows adjacent the line.

In the embodiment of the invention shown in Figs. 1 to 3, the improvement is shown in connection with a boiler 1 supported by the usual pedestal 2. The hot water delivery pipe 3 is connected with a T 4 at the top of the boiler, the T being connected with the boiler and having its lateral branch connected by a pipe 5 with a water heater 6. At the lower end of the boiler a pipe 7 leads to the range, and a pipe 8 connects this pipe 7 with the lower end of the heater 6. The intake pipe 9 for the cold water and the pipe 7 open into a common coupling, 45 which is a casting 10 having at its bottom an internally and externally threaded nipple 11 for connection with the pipe 7, and having intermediate its ends a threaded portion 12 for connection with the nipple 13 of the boiler. This coupling has two longitudinally extending passages, a passage 14 which places the pipe 7 into communication with the boiler, and a passage 15 which places the pipe 9 into communication with the boiler. The casting has a lateral internally and externally threaded nipple 16 for

connecting the passage 15 with the pipe 9, and the passage 14 has its commencement at the upper end thereof flush with the bottom of the boiler, as indicated in Fig. 2. 60

The coupling has a polygonal portion 17 just above the nipple 16 for engagement by a wrench to turn the coupling, and the said coupling is provided at its top with an externally threaded portion 18 which is engaged by a cap 19. This cap 19 has lateral openings 20 intermediate its ends, and a valve 21 is mounted for movement in the cap, the said cap constituting, in effect, a valve casing. The cap has a vent 22 at its 70 top, to permit the easy movement of the valve, and the valve co-operates with the upper end of the coupling as a seat.

This valve normally closes the inlet, but it may be easily lifted under pressure to 75 permit the entrance of water to the boiler. The valve, however, absolutely prevents re-gurgitation from the boiler into the water main.

In the embodiment of the invention shown 80 in Figs. 4 to 7, inclusive, the boiler 23 is supported by the pedestal 24, and the outlet 25 for the hot water supply 26 is at the top. The cold water from the cold water supply 27 enters the boiler by way of a pipe 28 85 which opens into the coupling 29 at the bottom of the boiler. This coupling is similar to the coupling 10, having two passages, one opening flush with the bottom of the boiler and the other opening at the top of the 90 coupling in the same manner as the passage 15. The only difference between the coupling shown in Fig. 4 and that shown in Fig. 1 is in the valve construction at the top. This construction comprises a cap 30 which 95 is threaded on to the upper end of the coupling, and the said cap has lateral passages 31 for permitting the flow of the water from the coupling into the boiler.

A valve 32 co-operates with the upper end 100 of the coupling, and this valve has a stem 33 which is movable in a guide extension 34 of the cap. A coil spring 35 normally acts to seat the valve, and the said spring is adapted to yield under the water pressure 105 to permit the entrance of the water from the main.

It will be noticed from an inspection of Fig. 2 that the cap 19 has an outwardly extending marginal flange 36 just above the 110 lateral passages, and the cap 30 has a similar petticoat 37 at the same point. These petti-

coats deflect the water outwardly and downwardly so that as it enters the boiler it cannot pass to the top of the boiler, but is driven toward the bottom. By the provision of the 5 flanges which are, in effect, deflectors, the entering water is forced against the bottom of the boiler, thus flushing the same, and preventing the deposit of sediment which would tend to choke the outlet. The mechanism 10 at the top of the coupling is a controller and guard, for controlling the inflow of the water and for guarding against re-gurgitation.

I claim:

- 15 1. A coupling for connecting boilers to intake and discharge pipes and adapted to be arranged in an opening in the bottom of the boiler and to extend above and below the bottom of the boiler, said coupling having two longitudinally extending passages, 20 one of the passages opening at the bottom of the coupling and adapted for connection with the discharge pipe, and the other opening laterally near the bottom and adapted 25 for connection with the intake, said last named passage opening at the top of the coupling, and the other of the said passages opening at the level of the bottom of the boiler, a cap having threaded engagement 30 with the top of the coupling, the cap having oppositely arranged ports, and a valve in the cap normally closing the passage and adapted to be lifted by the water pressure, 35 said cap having means for deflecting the entering water outwardly and downwardly, and a spring normally holding the valve closed.
2. A coupling for connecting boilers to intake and discharge pipes and adapted to 40 be arranged in an opening in the bottom of the boiler and to extend above and below

the bottom of the boiler, said coupling having two longitudinally extending passages, one of the passages opening at the bottom of the coupling and adapted for connection 45 with the discharge pipe, and the other opening laterally near the bottom and adapted for connection with the intake, said last named passage opening at the top of the coupling, and the other of the said passages 50 opening at the level of the bottom of the boiler, a cap having threaded engagement with the top of the coupling, the cap having oppositely arranged ports, and a valve in the cap normally closing the passage and 55 adapted to be lifted by the water pressure, said cap having means for deflecting the entering water outwardly and downwardly.

3. A coupling for connecting boilers to intake and discharge pipes and adapted to 60 be arranged in an opening in the bottom of the boiler and to extend above and below the bottom of the boiler, said coupling having two longitudinally extending passages, 65 one of the passages opening at the bottom of the coupling and adapted for connection with the discharge pipe, and the other opening laterally near the bottom and adapted for connection with the intake, 'said last named passage opening at the top of the 70 coupling, and the other of the said passages opening at the level of the bottom of the boiler, a cap having threaded engagement with the top of the coupling, the cap having oppositely arranged ports, and a valve in the cap normally closing the passage and adapted to 75 be lifted by the water pressure.

JOSEPH J. McCANN.
